Patented July 7, 1914.

2 SHEETS--SHEET 2.

UNITED STATES PATENT OFFICE.

CASPER FAUST, OF OSHKOSH, WISCONSIN.

BRIDGE-GATES.

1,102,254.

Specification of Letters Patent.

Patented July 7, 1914.

Application filed February 17, 1914. Serial No. 819,264.

To all whom it may concern:

Be it known that I, CASPER FAUST, a citizen of the United States, and resident of Oshkosh, in the county of Winnebago and State of Wisconsin, have invented certain new and useful Improvements in Bridge-Gates; and I do hereby declare that the following is a full, clear, and exact description thereof.

10 My invention refers to swinging bridges, its object being to provide a simple, economical and effective set of guard-gates therefor, the arrangement and construction being such that the diametrically opposite 15 gates are connected in pairs, whereby incoming gates from both approaches are simultaneously closed followed by closure of the outgoing gates.

One of the particular objects of my present invention is to provide a gate-actuating mechanism all connected above ground, whereby economy in insulation is effected due to the fact that it is not necessary to excavate under the abutments for installation.

25 With the above and other objects in view the invention consists in certain peculiarities of construction and combination of parts as set forth hereinafter with reference to the accompanying drawings and subsequently claimed.

30 In the drawings Figure 1 represents a plan view of a horizontally swinging bridge and its abutments equipped with gates embodying the features of my invention, parts being broken away and in section to more clearly illustrate details of construction; Fig. 2, a longitudinal sectional view of the same, the section being indicated by line 2-2 of Fig. 1; Fig. 3, a detailed cross-section of the bridge showing the gate-actuating mechanism attached thereto, the section being indicated by line 3-3 of Fig. 1, and Fig. 4, a detailed cross-section through the abutment, showing one of the guard gates and its connected actuating rod, the section being indicated by line 4-4 of Fig. 1.

40 Referring by characters to the drawings, 1, 1, represent the abutments of a horizontally swinging bridge 2 of any desired construction. Each abutment is provided with a pair of pillars 3 at points intersecting the walk and street line or curb. These pillars 45 have mounted therein the posts 4 of sidewalk and roadway gates 5, preferably of the

lattice-work type. Alined with the curbing of each abutment in juxtaposed position to the pillars are a pair of guide-blocks 6 carrying anti-friction rollers, between 60 which is slidably mounted sections of gate-actuating rods 7, 7', the same being provided with squared sections which engage the slide-blocks to thus prevent the rods from twisting in their seats. The abutment 65 rod sections are connected to the gates by links 8, the fulcrum points of which links are so arranged that when the gates are closed they form locks to prevent movement thereof in either direction except 70 through a positive movement imparted to the actuating rods. Thus the gates are automatically locked in their closed position, in which position they extend across both the roadway and sidewalk. 75

While I have shown and described one specific form of gate, it is obvious that I may, without departing from the spirit of my invention, gear connect the actuating rods to any type of gate. 80

The ends of the rod sections 7, 7', adjacent to the edge of the abutment are provided with coupling members 9, 9, 9', 9', respectively. These coupling members are in the form of upwardly projecting U-shaped 85 heads which are adapted to interlock with corresponding downturned coupling members 10, 10, 10', 10', which are carried at the ends of gate-actuating rod-sections 11, 11, 11', 11'. The last mentioned series of 90 rod sections are slidably mounted in blocks 12, which blocks are carried by the bridge. Hence each gate-actuating rod is composed of two sections one of which is carried by the abutment and the other alined section is 95 mounted upon the swinging bridge.

The inner ends of the bridge-carried rod-sections 11 are disposed upon diametrically opposite sides of the bridge and are connected by a transversely disposed rock-shaft 13, 100 which rock-shaft is suitably journaled in bearings that depend from the lower side of the bridge, as shown. The ends of the rock-shaft 13 are provided with lever-arms 14, 14', the lever-arm 14 being in pin and slot 105 connection with the inner end of one of the gate-actuating rod sections 11, while the opposite lever 14' is connected by a link 15 to the downwardly extended leg 15' of the opposite rod section 11, the said leg being 110 adapted to play within a slot 15'' that is formed in the bridge floor. Thus it is obvi-

ous that the diametrically oppositely disposed gates are connected and actuated simultaneously. The gate-actuating means comprises a stud-shaft 16 that is journaled in a bearing with which the overhead structure of the bridge is provided. The stud-shaft has secured thereto a lever-arm 17, which lever-arm is in pin and slot connection with that gate-actuating rod-section 11 5 having the downwardly extended leg 15'. The stud-shaft carries a gear-wheel 18, which gear-wheel is adapted to be thrown into clutch with a motor A by means of manual shift of a clutch-plate 19, which 10 clutch-plate carries a gear element that is adapted to transmit motion from the motor to said stud-shaft. The diametrically opposite set of gates, which are connected to the abutment-actuating rod section 7, are actuated by mechanism similar in construction to that just described, the bridge-carried actuating rod sections 11', being similar to that previously mentioned. These rod sections are 15 connected by a suitable lever mechanism to a rock-shaft 21, which rock-shaft is similar in every respect to that previously described. The second set of actuating rod sections 11' are operated by a stud-shaft 16' carrying mechanism similar to that previously described, the gear of which shaft is adapted to be connected to the motor through shift 20 of the clutch-plate.

By this arrangement the motor and actuating mechanism for the two sets of gates is 25 all arranged at the positions centrally of the bridge and to one side thereof, whereby it may be conveniently controlled by a single operator, but it is understood that I may, without departing from the spirit of my invention, operate each connected set of gates from opposite sides of the bridge, if desired. It is also manifest that, while I have shown and described the incoming and outgoing gates as being under control of a motor, I 30 may, without departing from the spirit of my invention, utilize a hand power mechanism of any desired type, the essential element being that the incoming gates are operated simultaneously, succeeded by a simultaneous operation of the outgoing gates to thus insure clearing of the bridge and avoidance of accidents. It is also within the scope of my invention to utilize a single set of the diagonally arranged gates, in which instance 35 the said gates would be of a length to extend

entirely across a comparatively narrow roadway, but, under all conditions the actuating mechanism for operating the gates would be arranged above the surface to eliminate cost of installation.

60

I claim:

1. The combination of a swinging bridge with its abutments, and a swinging guard gate mounted above each abutment upon diametrically opposite sides thereof, a longitudinally disposed slideable actuating rod section in operative connection with each gate, each of said rods being mounted above its corresponding abutment, a coupling member carried at the opposite end of each rod section, a pair of rod-sections slidably mounted upon the bridge at opposite sides thereof and extending in opposite directions, coupling members carried at the outer ends of the same for engagement with the coupling members of the abutment gate-actuating rod sections, a transversely disposed rock-shaft carried by the bridge and mounted thereunder, lever mechanism connecting the rock-shaft and each gate-actuating rod section of the bridge, and actuating mechanism for said bridge rod sections.

65

2. The combination of a swinging bridge with its abutments, and a pair of swinging gates mounted upon each abutment, a longitudinally disposed slideable actuating rod section in link connection with each gate, coupling members carried at the free ends of each rod section, slideable rod sections mounted upon the bridge each adapted to be aligned with a companion abutment actuating rod, a coupling member at the outer end of each of the bridge rod sections for engagement with the corresponding member of its companion abutment rod section, a pair of rock-shafts arranged transversely of the bridge, lever mechanism connecting each rock-shaft with the diametrically opposite bridge-carried rod-sections, and means for actuating the shaft-connected actuating rods independently.

70

75

80

85

In testimony that I claim the foregoing I have hereunto set my hand at Milwaukee in the county of Milwaukee and State of Wisconsin in the presence of two witnesses.

CASPER FAUST.
